JULIAN GORDON KNIGHT, OF BROOKLYN, NEW YORK

FIXTURE SUPPORT

Application filed March 16, 1925. Serial No. 15,815.

The present invention relates to the supporting of electric light fixtures from outlet boxes.

The present practice of supporting fixtures by means of a so-called "fixture stud" secured to the top of the box is objectionable because of the fact that the stud projects down into the box, occupying considerable space and interfering more or less with the wiring.

The objects of this invention are to provide an improved box construction and a support for the fixture which will not take up room within the box, thus leaving the interior of the box free for wiring and enabling the use of a shallow box construction; and to provide such a support in a simple, inexpensive and entirely practical form.

In the drawing accompanying and forming part of this specification, the invention is illustrated embodied in two different forms, but I wish it understood that the structure may be further modified without departure from the broad spirit and scope of the invention.

Figure 1 is a cross sectional view of the box with the invention incorporated therein, illustrating a fixture pipe supported thereby.

Figure 2 is a plan view of the box top broken away at one side to show the box structure.

Figure 3 is a cross sectional view illustrating the fixture support incorporated as an integral part of the box top.

The box 5 may be of any usual or special construction and is here shown as made up of two complementary box sections 6, 7 having overlapping end portions secured together by lugs 8 having reduced shanks 9 extending through registered openings in the overlapping portions and headed over at the outside of the box wall as at 10. These lugs project at the inside of the box wall and are formed with screw seats 11 to receive the screws 12 for securing the cover or covers in place.

The screw lugs thus serve the double purpose of providing seats for the cover fastening screws and forming rivet fastenings

for securing the box wall sections together. As shown particularly in Figure 2, abrupt shoulders 13 are provided at the back of the screw lug, at the root of the rivet shank, which shoulders abut the inner face of the box wall, forming in effect a head for the inner end of the rivet shank and at the same time a firm bearing for the screw lug against the side wall of the box. In addition to fastening the overlapping parts together the rivet shank by its passage through the two thicknesses of metal forms a reinforcement for the screw lug, strengthening and preventing bending of the same under any unusual strains. Another advantage of this construction is that the tensioning of the screws to secure the top firmly in place has a tendency to bind the parts all the more firmly together.

The fixture support is in the form of a cup shaped socket 14 mounted on the top 15 of the box, open to the interior of the box and having internal screw threads 16 to take the correspondingly threaded end of the hickey 17, insulating joint or the like, or even the threaded end of the fixture pipe 18 itself, in accordance with different requirements.

As shown in Figures 1 and 2, the fixture socket is made as a separate unit having an outstanding base flange 19 resting on the box top and lugs 20 partially severed therefrom extended down through openings 21 in the top and bent under against the inner face of the top at 22. In this form the box top has a central opening 23 in line with the threaded socket in the fixture supporting cup.

The form of the invention disclosed in Figure 3 differs from that just considered in that the fixture socket is formed as an integral part of the box top. In manufacturing this form of the invention the box top is usually operated on in a suitable punch or punches to produce the upwardly projecting hollow integral cup, after which it is only necessary to form the internal screw threads.

The special form of hickey shown in Figure 1 consists of a pipe section slotted

longitudinally from one end of the same to provide wire receiving openings 24. To prevent the separated end portions 25 formed by the slots 24 from crowding together as the hickey is screwed into the 5 socket, the top of the socket may be bulged downwardly as shown at 26 to act as a "spreader" for these parts. This produces an interlock between the hickey and the 10 socket and prevents the hickey from becoming loosened by vibration and the like.

With this improved construction, practically the entire interior of the box is available for wiring purposes since the fixture 15 support occupies no part of the box interior. This means that the same wiring accommodations may be provided in a box of shallower construction than in the old style box, employing a stud projecting down into 20 the box for the support of the fixture. This construction also has many advantages in the way of greater simplicity and less expense.

In addition to giving more room for wiring, this box construction provides plenty 25 of room for flush receptacles and the like and the socket while ready for use when desired, is out of the way and does not interfere with the full use of the interior of the 30 box in case the fixture supporting feature is not needed in some instances.

The top of the box is shown as substantially square to provide increased anchorage for the box and a more firm support for 35 the fixture. This square top, it will be seen, forms a wider base, capable of supporting heavier fixtures and makes it easier to level the box in the concrete.

What is claimed is:

40 1. An outlet box having an opening in the top of the same for the passage of a fixture mounting member and a pressed metal hollow fixture support closed at its upper end and having a base secured to the 45 top of the box in position with the closed hollow portion of the support in registry with the opening in the top, said hollow closed portion of the support projecting above the top of the box and being internally screw threaded to match the complementary screw threads on a fixture mounting member.

2. An outlet box having an opening in the top of the same for the passage of a 55 fixture mounting member and a hollow fixture support closed at its upper end and having a base secured to the top of the box in position with the closed hollow portion of the support in registry with the opening 60 in the top, said hollow closed portion of the support projecting above the top of the box and being internally screw threaded to match the complementary screw threads on a fixture mounting member, said hollow fixture support being secured in inverted

relation on the top of the box with its closed end uppermost and with a screw-threaded interior of the same located above the top of the box, so as not to take up useful wiring space within the box.

3. In combination with an outlet box having an opening in the top of the same, a hollow fixture supporting stud mounted on top of the box over the hole therein and having an internally screw-threaded socket in line with said hole, enabling the fixture supporting means to be passed up through the hole in the top of the box and engaged in said socket and be thereby supported without taking up wiring space within the 80 box.

In witness whereof, I have hereunto set my hand this 26th day of February, 1924.

JULIAN GORDON KNIGHT.
